UNITED STATES PATENT OFFICE.

EMMETT W. STULL AND GEORGE B. SCHLEY, OF MILWAUKEE, WISCONSIN, ASSIGNORS
TO ALLIS-CHALMERS COMPANY, A CORPORATION OF NEW JERSEY.

MULTIPLE-VOLTAGE CONTROLLER.

992,289.

Specification of Letters Patent. Patented May 16, 1911.

Application filed September 30, 1909. Serial No. 520,313.

To all whom it may concern:

Be it known that we, EMMETT W. STULL and GEORGE B. SCHLEY, citizens of the United States, and residents of Milwaukee, in the county of Milwaukee and State of Wisconsin, have invented certain new and useful Improvements in Multiple-Voltage Controllers, of which the following is a full, clear, and exact specification.

10 Our invention relates to multiple voltage control.

One of the most efficient ways to control an electric motor is by changing its armature connections from one set of mains to another of a multiple voltage system. It has heretofore been customary in multiple voltage controllers to break the armature circuit when such a change is made, in order to prevent a short-circuit between any two of the multiple voltage mains. Such interruption of the armature circuit is sometimes undesirable. Moreover, upon a change of the armature connections from one set of mains to another of either higher or lower voltage, there is a tendency to produce excessive surges of current through the armature. In order to prevent these surges of current it has been proposed to insert a resistance in series with the armature for a while after such a change in the armature connections is made.

It is the object of our present invention to provide a multiple voltage controller by which a motor armature or other translating device may be changed from one set of mains to another of a multiple voltage system without breaking the armature circuit, without danger of short-circuiting any two of the mains, and without producing excessive surges of current in the armature upon either increase or decrease of the impressed voltage.

Our invention comprises a multiple voltage controller which is arranged to connect a translating device across different sets of mains of a multiple voltage system, to change the translating device from one set of mains to another without interrupting its circuit, and to connect a resistance in series with such device upon making such a change either to increase or to decrease the impressed voltage. In its preferred form, our controller is of the drum type, and can connect the translating device across any

set of mains of a multiple voltage system and change it from such set to another set in the manner described above. In the form illustrated, a manually variable resistance is connected in series with the translating device when the latter is changed from one set of mains to another of higher voltage, and a resistance which is subsequently automatically cut out is connected in series with such device when it is changed from one set of mains to another of lower voltage. In the arrangement shown this latter resistance is cut in by raising one of the fingers of the controller as the latter in its backward movement passes certain positions.

Other features of our invention will appear hereinafter.

Figure 1 is a view showing a part of a controller embodying our invention; and Fig. 2 is a diagram showing the electrical connections of such controller.

The controller drum 10, mounted on a shaft 11, as here illustrated has nine operative positions and is divided into two electrical sections 14 and 15, each of these sections having a number of electrically connected contact segments 16 thereon. These segments of the controller coöperate with the contact fingers 17 to 26 inclusive. The upper and lower contact fingers 17 and 26 respectively are connected to the two terminals of the armature 27 of the motor A to be controlled. Fingers 18 and 25 are connected respectively to the two mains 28 and 30 and finger 22 is connected to the main 29 of a multiple voltage system. In the three-wire multiple voltage system here illustrated, the voltages are 90, 160, and the sum of these two, 250, as usual. Connected to the contact fingers 18, 19, and 20 is a sectional resistance 31, while a similar resistance 32 is connected to the contacts 23, 24, and 25. Another resistance 37 is connected between contact finger 21 and main 29. The field winding 33 of the motor A is preferably permanently connected between the outside mains 28 and 30 of the multiple voltage system, and controlled by a separate switch 34. A main switch 35 controls the circuits of the motor and the controller. The strength of the field winding 33 may be regulated by a rheostat 36, which, if desired, may be combined with the controller 10.

22

Mounted on the shaft 11 of the controller are two arms 38 and 39, one or the other of which when the controller shifts the motor armature from one set of mains to another 5 engages a finger 40 hinged to one end of a lever 41 pivoted at 42. A rod 43, connected to the opposite end of the lever 41, is connected to the piston of a dash-pot 44 pivoted on a fixed support 45. A spring 46 tends 10 to hold this lever 41 against a stop 46^a. A link 47 connects one arm of the lever 41 and one end of another lever 48 which is pivoted at a point 49. Located at the other end of said lever 48 is the contact finger 22, the movement of which is controlled by the 15 action of the arms 38 and 39 and the dash-pot 44.

The operation of the controller is as follows: When the drum 10 is moved into position 1, the switches 34 and 35 being closed, the motor armature 27 is connected between the mains 29 and 30 with the entire resistance 32 in circuit. The motor now starts. As the controller is moved to positions 2 and 25 3 respectively, the two sections of the resistance 32 are cut out of circuit successively. In position 3, the first running position of the controller, the armature 27 has impressed thereon the full 90 volts between the mains 30 29 and 30. As the controller is moved from position 3 to position 4, the contact fingers 20, 21, and 22 are first connected together, thus connecting the mains 28 and 29 together through the entire resistance 31. This connection lasts only for an instant, as immediately thereafter the contact fingers 21 and 22 break connection with the segments with which they had at first engaged. About 35 this time the resistance 32 is again included 40 in the armature circuit. The motor armature is now momentarily connected across the high voltage outside mains, but both resistances 31 and 32 are fully in circuit and prevent the impressing of a too high voltage 45 on the motor armature. Next, the fingers 21, 22, and 23 are connected by the drum section 15, thus connecting the mains 29 and 30 together through the entire resistance 32. Immediately, however, the contact finger 23 is disconnected from the drum 15. Thus in position 4 the motor armature is connected between the mains 28 and 29 with the entire resistance 31 in circuit therewith. As the drum is moved to positions 5 and 6 50 respectively, the two sections of the resistance 31 are successively cut out. In position 6, the second running position of the controller, the armature has impressed thereon the full 160 volts between the mains 28 and 29. As the controller is moved from position 6 to position 7, the contact fingers 21, 22, and 23 are again momentarily connected together to connect the mains 29 and 30 through the entire resistance 32. Immediately, however, the contact fingers 21 and 22

leave the segments of drum section 15 with which they had been in engagement in position 6. The motor armature 27 is now connected between the outer mains 28 and 30 with the full resistance 32 in circuit. As the controller is moved into positions 8 and 9 respectively, the two sections of resistance 32 are again successively cut out of circuit. In position 9, the third and last running position of the controller, the armature 27 has impressed thereon the full 250 volts between the outer mains 28 and 30. As the controller has been moved through these positions 1 to 9 the motor armature circuit has not been interrupted, short-circuiting of the mains 80 of the multiple voltage system being prevented by means of resistances 31 and 32. During the backward movement of the controller, the reverse of the operation just described takes place, with the exception that 85 the resistance 37 comes into service. When the controller moves from position 7 to position 6, or from position 4 to position 3, the arm 39 or 38 engages the finger 40 and through it moves the levers 41 and 48 against the action of the spring 46 to lift the contact finger 22 away from its coöperating segments on the controller drum. The dash-pot 44 is so constructed that it does not retard this movement of the levers. The lifting of the contact finger 22 away from the controller drum breaks the short-circuit around the resistance 37, causing current to flow through the resistance 37 instead of through such short-circuit. The insertion of 90 this resistance 37 into the motor armature circuit prevents any excessive surges of current through the armature because of the generator action of the latter as it is changed from a set of mains of higher voltage to a 95 set of mains of lower voltage. When the controller has fully reached position 6 or position 3, the arm 39 or 38 passes out of engagement with the finger 40, and the spring 46 begins to move the contact finger 22 toward engagement with its coöperating contact on the controller drum. The dash-pot 100 retards this movement of the contact finger 22 until it has nearly reached the controller drum, when a by-pass in the dash-pot allows the finger to engage the drum segment with a snap. The resistance 37 is only cut into circuit during the backward movement of the controller, as during the forward movement of the controller the finger 40 swings about its hinge when engaged by the finger 38 or 39, and does not transmit motion to the lever 41 and through it to the contact finger 22.

110 For the sake of simplicity we have shown our invention as applied to a three-wire multiple voltage system, but it is equally applicable to other multiple voltage systems.

115 The number of sections of the resistances 31, 32, and 37 may be varied, if desired, to 120

suit the requirements of any particular system. Also any desired number of motors may be simultaneously controlled.

Many other modifications can be made in the precise arrangement shown and described, and all such which do not involve a departure from the spirit and scope of our invention we aim to cover in the following claims.

10. What we claim as new is:

1. In a multiple voltage controller, the combination of coöperating fixed and movable members arranged to connect a translating device to different sets of multiple voltage mains and to change the connections of such device from one set of such mains to another without interrupting the circuit, a resistance, and means mechanically operated by a movement of the controller which

15 changes the connections of such translating device from one set of the multiple voltage mains to another set of lower voltage, to insert such resistance in series with the device between it and the lower voltage mains.

20 2. In a system of control, a translating device, multiple voltage mains, a resistance, and a controller comprising coöperating fixed and movable members arranged to connect said translating device to different sets of said multiple voltage mains and to change the connections of such device from one set of such mains to another without interrupting the circuit, and means mechanically operated by a movement of the controller

25 which changes the connections of such translating device from one set of the multiple voltage mains to another set of lower voltage to insert such resistance in series with the device between it and the lower voltage

30 mains.

3. In a multiple voltage controller, the combination of a drum, contact segments mounted on said drum, contact members coöperative with said segments, said controller arranged to connect a translating device to different sets of multiple voltage mains and to change the connections of such device from one set of such mains to another without interrupting the circuit, a resistance, and

35 means mechanically operated by a movement of the controller which changes the connections of such translating device from one set of the multiple voltage mains to another set of lower voltage to insert such resistance in series with the device between it and the lower voltage mains.

40 4. In a system of motor control, a motor, multiple voltage mains, a resistance, a lever arrangement for cutting in and out said resistance, and a controller arranged to change the connections of the motor armature from one set of mains to another of lower voltage while maintaining the continuity of the circuit of said armature and as such change is

45 being made to insert, by means of said lever

arrangement, said resistance temporarily in the armature circuit and in series with the main to which an armature terminal is being changed.

5. In a multiple voltage controller, the combination of coöperating fixed and movable members arranged to connect a translating device to any set of mains of a multiple voltage system and to change the connections of such device from one set of such mains to another without interrupting the circuit, a resistance, and means mechanically operated by a movement of the controller which changes the connections of such translating device from one set of the multiple voltage mains to another set of lower voltage to insert such resistance in series with the device between it and the lower voltage mains.

6. In a multiple voltage controller, the combination of coöperating fixed and movable members arranged to connect a translating device to any set of mains of a multiple voltage system for rotation in the same direction, and to change the connections of such device from one set of such mains to another without interrupting the circuit, a resistance, and means mechanically operated by a movement of the controller which changes the connections of such translating device from one set of the multiple voltage mains to another set of lower voltage to insert such resistance in series with the device between it and the lower voltage mains.

7. In a system of motor control, the combination with a multivoltage supply circuit, a motor, a resistance, mechanically operated means governing said resistance, of a controller constructed and arranged to change the connections of the motor armature from any set of mains of said supply circuit to another without interrupting the circuit of said armature, and to coöperate with said means to insert said resistance temporarily between two of the mains of the supply circuit and also in the armature circuit as said change is made.

8. In a system of motor control, the combination of multivoltage supply mains, a motor, a resistance, a member for cutting said resistance in and out of circuit, and a controller mechanically coöperating with said member, said controller being constructed and arranged to change the connections of the motor armature from any set of said mains to another and as such change is made to insert said resistance between those mains between which an armature terminal is being changed.

9. In a motor controller, a system of levers, a contact finger adapted to be effected only in one direction of motor rotation, the initial movement of said finger being controlled by said system, a dash-pot, and a member arranged to coöperate with said system for transmitting motion to said con-

contact finger, said dash-pot being so constructed as to permit movement of the contact finger freely in one direction but to retard movement in the other direction.

5 10. In combination with an electric motor, of a resistance, lever operated means for connecting said resistance in series with the motor-armature whenever the motor operates temporarily as a generator, means for short-circuiting said resistance, and retarding mechanism for the short-circuiting means.

10 11. In a controller, the combination of a member, a contact finger, the movement of which is controlled by said member, a re-

tarding device, and means arranged to co-operate effectively only in one direction, with said member for transmitting motion to said contact finger, said retarding device being so constructed as to permit movement of the contact finger freely in one direction but to retard movement in another direction. 20
